UNITED STATES PATENT OFFICE

RAGNAR WILLIAM WINBERG, OF EAST ELMHURST, LONG ISLAND, NEW YORK

CURTAIN THREADER

Application filed July 3, 1930. Serial No. 465,732.

This invention relates to curtain rod guides and has for its object the provision of a device of this character which may be placed upon the end of a curtain rod when a curtain is being threaded thereon and which will eliminate any possibility of tearing the curtain or pulling the hem of a new or freshly laundered curtain.

Another object of the invention is to provide a device which may be simply and inexpensively constructed from a single piece of sheet metal and which will protect a delicate curtain against being torn by the end of the usual hollow curtain rod with its sharp edges, when said curtain is being threaded theron, as well as guide the movement of the end of the rod more quickly through the hem in said curtain, the device being particularly desirable when a large number of curtains are to be threaded at one time, or when speed is an important factor.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawing, which latter show embodiments of the invention as at present preferred.

In said drawing:

Fig. 1 is a perspective view of the device placed on a curtain rod, and showing a cut-away portion of the hem on the curtain.

Fig. 2 is a front elevation of the device showing in broken lines the spring clip which secures the device to the rod.

Fig. 3 is a section taken on line 3-3 of Fig. 2.

Fig. 4 is an end elevation of the device.

Fig. 5 is a plan view of the metal blank from which the device is formed.

Similar reference characters refer to similar parts throughout said drawing.

Referring now more particularly to said drawing, the embodiment is preferably stamped from a single piece of brass or other

sheet metal and comprises side portions 10 and 11 with tapering ends 10' and 11' and a spring clip portion 12, integral with one of said side portions, said clip portion having a coextensive tongue portion 13 on the end thereof which engages one side of a standard curtain rod 14, securing the device to said rod when the curtain is being placed thereon.

The clip portion of the blank is preferably tempered to give it the desired clamping action and is bent inwardly at 12' as seen in Fig. 3, after which the blank is bent to the position indicated in Figs. 3 and 4. Curved corners 15 as well as a curved head 16 are provided in order that the device may pass through the curtain more readily and with less chance of damaging the curtain. The edges 17 of the metal blank may then be secured together by means of welding, soldering or mere crimping, if desired.

When a curtain 18 with a hem 19 is to be threaded with a standard curtain rod 14 the device is placed upon the end of the rod and is held in place by means of the tongue portion of the spring clip. The rod is then run through the hem of the curtain and the device is then easily slipped off.

The device may be constructed in different sizes and shapes to fit the various sizes and shapes of standard curtain rods. The tongue 13 formed as the extremity of the clip portion is of materially greater width than the clip portion and thus when the device is attached to a curtain rod, the tongue has a much greater area of contact with the latter than were it merely the width of the clip portion. By reason of this construction, a relatively narrow clip serves as the single means for maintaining a comparatively great surface area in frictional engagement with the rod and the tongue being bent inwardly from the open end of the device, there are no openings on the exterior surface of the latter to impinge on the goods of the curtain when the device is used for the insertion of a rod in the hem.

The hereinbefore described construction admits of considerable modification without

departing from the invention; therefore, it is the wish not to be limited to the precise arrangements shown and described, which are as aforesaid, by way of illustration merely. In other words, the scope of protection contemplated is to be taken solely from the appended claim, interpreted as broadly as is consistent with the prior art.

What is claimed is:

- 10 A curtain rod guide stamped from a single piece of sheet metal and including front and rear portions, said front and rear portions being inwardly turned, forming a pocket to receive one end of a curtain rod,

15

and terminal contacting portions at one end of said body for guiding said curtain rod between the opposed walls of a curtain hem, and a resilient strip of metal integral with the opposite end of one of said portions and bent inwardly from the rear edge thereof into said pocket, said resilient strip terminating in a tongue extending laterally beyond its side edges to provide a frictional bearing member for contact with a received curtain rod over a comparatively great surface area of the latter.
